(57) **CLAIM**

The ornamental design for a printer stamp, as shown and described.

DESCRIPTION

FIG. 1 is a front view showing my new design for a printer stamp;

FIG. 2 is a top plan view thereof;

FIG. 3 is a front perspective view thereof;

FIG. 4 is a bottom plan view thereof;

FIG. 5 is a rear view thereof;

FIG. 6 is a left side view thereof;

FIG. 7 is a right side view thereof; and,

FIG. 8 is a rear perspective view thereof.

The broken lines in FIGS. 1, 4 and 7 depict portions of the article that form no part of the claimed design.

1 Claim, 8 Drawing Sheets
